UNITED STATES PATENT OFFICE.

JOHN W. CULMER, OF NEW BRIGHTON, PENNSYLVANIA.

COMPUTING-SCALE.

SPECIFICATION forming part of Letters Patent No. 552,826, dated January 7, 1896.

Application filed February 16, 1895. Serial No. 538,673. (No model.)

To all whom it may concern:

Be it known that I, JOHN W. CULMER, a citizen of the United States, residing at New Brighton, in the county of Beaver and State 5 of Pennsylvania, have invented certain new and useful Improvements in Computing-Scales; and I do hereby declare the following to be a full, clear, and exact description of the invention, such as will enable others skilled 10 in the art to which it appertains to make and use the same, reference being had to the accompanying drawings, and to the letters of reference marked thereon, which form a part of this specification.

15 This invention relates to computing-scales of the platform type; and its object is to improve the means by which the ordinary parts and mechanisms for receiving actual weight and transmitting its effect to the weight-indicating mechanism may be united to and co-ordinated with the beam of a computing-scale.

In the accompanying drawings, wherein like letters represent the same parts throughout, Figure 1 is a front elevation of a computing platform-scale provided with my improvements; Fig. 2, a top plan of the same; Fig. 3, a vertical lengthwise section of the same; Fig. 4, a plan view of my lever and 20 trolley-bar with some convenient balancing devices added; Fig. 5, an end view of the same; Fig. 6, a detached front elevation of the trolley-bar, the trolley, and the linked sliding poise by which the connection is made 25 with the computing - beam; Fig. 7, an end view of the same, showing the trolley-bar and the computing-beam in section; Fig. 8, a front 30 interior view of the aforesaid linked sliding poise upon the computing-beam; Fig. 9, an 35 end view thereof, and Fig. 10 a top view of 40 the same.

45 A is the ordinary hollow base of the scale, having at its rear a pair of standards B, each with a bearing *a* on its inner face. The standards support a plate C, which extends far to the right, and midway of this plate rises a standard D, and this completes the frame of the scale.

50 E is the weighing-platform, having the customary feet *b*, and these bear upon the levers *c* and *d*, which, with their usual pivots, links, and supports, constitute the ordinary system,

within the hollow of the scale-base, for pulling down the vertical rod *e*, that, in a non-computing scale, would actuate the lever operating the weighing-beam. In this construction it actuates the lever now to be described.

F is my trolley-supporting lever. It consists of two forwardly-projecting parallel arms *f*, joined at their rear ends by a base *g*, which 55 may be straight or curved, as taste, convenience, or other circumstance may suggest. Each of the arms is provided with a fulcrum-pivot *h* for the balancing of the lever upon its support. From the lever-base projects at 60 right angles an arm *i*, the front end of which is pivoted to the top of the vertical rod already described as proceeding from the scale-base. The lever being seated by its fulcrum-pivots in the bearings *a* of the base-standards, 65 the pull of the vertical rod upon the arm *i* of the lever will depress the front of the latter. Across this otherwise vacant front is the 70 trolley-carrying bar *G*, supported at the ends of the arm *f* of the lever, and this bar must 75 be so seated in the arms as to be in true parallel with the fulcrum-pivots, which are to be parallel with each other. This may be done by making the seats in the arms longer than the width of the bar and passing a screw 80 through bar and seat, as indicated in Figs. 4 and 5; but this is mere mechanical detail for the scale-maker to decide.

Preparatory to weighing or computing anything the lever F must be in balance. There 85 are various familiar ways of adjusting balance, among them the addition of weights, as *k*, to the light end of the lever, these working adjustably on screw-stems projected from the 90 lever-base.

A scoop is sometimes used on the weighing-platform. To counterbalance this I may project a stem *l* from the base end of the aforesaid lever and mount upon it a screw-fastening balance-weight *m*, which, when the scoop 95 is on, is turned over to or toward the rear till the scoop is counterbalanced, and when the scoop is off the platform the balance-weight may be turned forward and assist in establishing the general balance of the lever.

100 H is a trolley, made wide and heavy at bottom to keep it upright. It has a pair of wheels *n* to support and move it upon the trolley-bar carried by the librating lever, and it may have

an under wheel o , engaged with the bottom edge of the trolley-bar, to assist in holding the trolley to the bar when the latter is pulled down. The upper part of the trolley forms 5 a standard, which in front is prolonged and projected into a curved finger-catch p , as shown in Figs. 3 and 7. Behind the finger-catch a shoulder r is formed, making a seat for the mechanism to be supported by the 10 trolley.

15 I is the computing-beam. It consists of two parallel bars, one above the other, with an interval between the proximate edges, and these bars are united at their ends. By means of 20 a pivot s , mounted in the center block t , forming part of the lower bar, the beam is properly supported and librated on the standard D , which is part of the framework of the scale. Scale-makers will graduate and mark the 25 three spaces afforded by the upper bar and the divided lower bar of the beam, according to the work and results desired from a particular scale; but one of the many practical arrangements I will now describe.

30 25 Take the left-hand section of the lower bar. The available marking-space begins at the straight edge of the block t and extends to the left till the boundary is reached of the end space within which can be exactly contained 35 the poise necessary to operate this part of the beam. The marking-space so available I divide into forty equal portions. Along the bottom each of these vertical marks represents a price-rate of one-quarter of a cent; 40 but along the top each mark represents one cent. This (the price-graduation of the beam) is therefore capable of doing its share in any computation involving a rate from five to sixty cents, with quarter-cent fractions. Take now 45 the upper bar of the beam. The space along this bar I mark off near the top into equal divisions to indicate value. Read along the top of these vertical marks, each mark indicates an increase of one cent and so co-operates 50 with the upper readings, above described, of the left lower bar. Read along the bottom, each mark indicates but one-quarter of a cent, and so corresponds with the lower readings 55 of the left lower bar. Along the bottom of this upper mark I mark the space off into pounds and half-ounces, so that articles may be weighed without computation, or the accuracy of the scale tested by an official 60 inspector. Take now the right-hand section of the lower bar. The resting-place of the poise for this bar is against the center block. The rest of the space I have marked off into pounds and ounces when read along the bottom of 65 the marks. There are no top readings, because it is designed to sometimes use this part of the lower bar and the poise belonging to it for purposes of tare, when the weight of vessels containing articles to be weighed is to be counterbalanced.

65 65 On the upper bar of the computing-beam is a sliding poise K , the resting-place of which is at the left-hand extremity of the bar. This

poise may be, as shown, cut away on its rear face to form pointers for the upper row of marks along the beam, and on its front face to 70 form a pointer for the lower row of marks. Of course, the weights of the poise are adjusted to enable the value-pointers to be at the rear of this poise, instead of on the front face, as they might be, if desired.

75 On the right-hand section of the lower bar of the beam is a sliding poise L , the resting-place of which, as already stated, is at the left-hand extremity of the section, against the center block. The straight front face of this 80 poise is a sufficient marker for reading along the single scale of weight-marks; but for convenience that face may be recessed, as shown, to emphasize the indicating to be done by the poise.

85 When prices or weights run above those provided for on the beam, movable poises, such as are usual in platform-scales, may be used on the swinging seat M , pivotally hung from a goose-neck N , projected from the right-hand extremity of the beam. This goose-neck may also be used to check excessive libration 90 of the beam by mounting on the framework an arm o with a pair of studs v on it, respectively above and below the goose-neck, as 95 shown.

95 100 Preparatory to an operation in weighing or computing, the beam I must be balanced. There are various ways of doing this, including the one I have shown, in which a balancing-weight P moves in and out upon a stem projected horizontally from another balancing-weight R , which moves up and down upon a vertical screw-stem w , bracketed at the left-hand extremity of the computing-beam. This 105 arrangement insures a nice balancing of the beam upon its fulcrum-pivot.

110 Upon the left-hand section of the lower bar of the beam is a sliding poise S , which is normally at home anywhere along the beam-section. It is hung in a link T by means of a bolt y in the top of the link, which bolt is axially traversed by a pin z , supported by and near the top of the poise, a recess a'' being 115 formed at the top of the poise to accommodate the bolt and the pin. This enables the poise to swing within the link and give necessary flexibility to the movements of the poise.

120 The poise S is provided with rollers b' journaled in the top extremities of the poise, and these fit on the top edge of the left-hand bar-section of the beam, without, however, bearing down upon the beam.

125 The link T , carrying the poise just mentioned, rests with its stem at its rounded bottom upon the shoulder r in the upper part of the trolley, and a shoulder-screw g' is passed through the trolley and the stem to make a flexible connection between link and trolley, 130 and hold them together when the latter pulls upon the former in the downward movement of the scale. This trolley-borne poise S is hollow, and has a lock U within it supported

by springs c' resting upon the floor of the poise, which normally press the lock up against the under edge of the left-hand bar-section upon which the poise slides. This under edge may 5 be toothed, if desired, in correspondence with the markings, to make a firm engagement with the upwardly-pointing prongs of the lock. The lock has a bearing d' upon each inner face. A thumb-lever W is pivoted at 10 the back and lower part of the poise, and has lugs e' by which it rests upon the bearings d' of the lock. It may have, also, a stop f' underneath to come upon the top surface of the finger-catch p forming the front upper extremity of the trolley, thus to prevent excessive depression of the springs when the lever 15 W is pressed down.

For the operation of the scale the lever F is put in balance upon its pivots by its 20 balancing-weights at the rear end, thus enabling it to support the trolley-bar G , the trolley H , and the poise S from its front end at the balancing-level. The computing-beam I is also put in balance by the balancing-weights at 25 its left-hand extremity, the poises K and L being in their respective resting-places, as already described. The poise S , though upon the lower bar of the beam, does not disturb nor enter into the balance, because it is supported by the trolley, and is therefore in the 30 balance of the aforesaid lever; and because the bar that supports the trolley is properly parallel, the poise S can be moved to and fro upon the lower bar of the beam without disturbing the beam-balance at any place of its rest. Now put weight upon the platform. The rod e pulls down the arm i , and so depresses the bar G and with it the trolley H , which, by means of the poise S , depresses 35 the left side of the computing-beam and so throws the beam out of balance. The balance is restored by moving out to the right either the poise K on the upper or the poise L on the lower bar.

40 Having regard to the system of graduations herein chosen for illustration, suppose the price of an article on the platform to be thirty cents per pound. Take the thumb-lever W and the finger-catch p between the thumb and forefinger and press upon the former, thus disengaging the lock U from the bottom edge of the computing-beam, and then move the poise S , by means of and with the trolley, till the upper pointer of the poise is at 45 the mark for thirty cents. Then release the thumb-lever, and the lock will again bear upon the edge of the beam. Next move the poise K along the upper bar until the beam balances and the pointer in the rear face of 50 that poise will tell the value of that article.

Suppose an article is to be only weighed. Place a standard one-pound weight upon the platform of the balanced and unoccupied scale, and set the poise K or the poise L at 55 the one-pound mark. Then move the poise S till the scale balances, which will be, let us say, when the lower pointer of that poise is at

the figure 8 on the lower line of readings. A mark is then made against that figure to denote the correct position of that poise whenever, in future, there is to be simply a weighing operation. Now remove the standard weight from the platform, put the article thereon, and the poise S being in its proper place for simple weighing move out either of 75 the other poises till the beam is in balance and the weight is told.

Suppose a vessel is put on the platform to contain the commodity. The tare of the vessel may be balanced either by adjustment of 80 the balance-weight m on the lever or by moving out the poise L , while the poise S is at its weight-mark, till the scale is in balance, and then proceed as before with the weighing or computing. 85

Having thus described my invention, and disclaiming anything shown or described in the Letters Patent of the United States Nos. 442,218 and 530,930, I claim the following:

The combination, in a platform computing 90 scale, of the hollow scale base; the pair of standards at the rear thereof; the bearings on the inner faces of said standards; the weighing platform supported upon and within the hollow base, and having the feet descending 95 the interior of said base; the pair of connected and pivoted levers within said base, adapted to the support of the aforesaid platform; the vertical rod pivoted to said levers and rising from said scale base; the lever, 100 supported by the aforesaid standards upon the scale base and provided with the pair of fulcrum pivots adapted to engage the bearings upon said standards, and having also the central forwardly projected arm pivoted to 105 the aforesaid vertical rod, the adjustable balancing weights at the rear, and the long straight bar at the front, parallel with the aforesaid fulcrum pivots; the broad based trolley, supported upon and moving along the 110 bar at the front of the aforesaid lever and having the pair of wheels resting upon said bar, and further provided with the shoulder in the upper part thereof; the link, supported at the top of the trolley and provided with 115 the screw adapted to flexibly connect said trolley and link; the hollow block, pivoted at the top to the upper part of said link and adapted to swing therein, and provided interiorly with the spring supported lock having an upward bearing; the plate resting on the pair of aforementioned standards of the scale base; the standard rising from said plate; the computing beam formed into two parallel bars and supported by said standard, 120 and having the center block adapted to the division of said beam into graduations, the fulcrum pivot adapted to librate the beam upon its standard, the gooseneck at the right hand end and the swinging seat dependent 125 therefrom, and the adjustable balancing weights at the other end of said beam; the sliding poises respectively on the upper bar of the beam, and on the right hand section of 130

the lower bar thereof—the upper bar of said beam being spaced and marked from left to right into graduations expressing value; the right hand section of the lower bar spaced and marked into graduations, from left to right, expressing weight; the left hand section of said lower bar spaced and marked into graduations, from right to left expressing price rates, and the said left hand section being passed through and engaged with the aforesaid hollow block in such manner as to

adapt said block to traverse said bar section between end and center block; the whole construction and arrangement as described, and for the purposes hereinbefore set forth. 15

In testimony whereof I affix my signature in presence of two witnesses.

JOHN W. CULMER.
